US00D475098S

(12) **United States Design Patent** (10) Patent No.: **US D475,098 S**
Manville (45) Date of Patent: **** May 27, 2003**

(54) **CRAFT KIT CONSTRUCTION
COMPONENT—LEG FORM**

(75) Inventor: **Richard B. Manville**, Los Angeles, CA (US)

(73) Assignee: **Mattel, Inc.**, El Segundo, CA (US)

(**) Term: **14 Years**

(21) Appl. No.: **29/157,887**

(22) Filed: **Mar. 26, 2002**

(51) LOC (7) Cl. **21-01**

(52) U.S. Cl. **D21/658**

(58) Field of Search **D21/386, 576,
D21/658; 446/97, 390, 483**

(56) **References Cited**
